TOP LOCK FOR OIL WELL PUMPS

Douglas M. Gall and Douglas G. Gall,
Taft, Calif.

Application March 29, 1948; Serial No. 17,706

10 Claims. (Cl. 103—219)

1

This invention relates in general to improvements in insert type oil well pumps.

In particular the invention is directed to, and it is an object to provide, a novel top lock for a suspended insert type oil well pump; such top lock being arranged to automatically become effective upon initial lowering of the pump into place, and to thereafter normally but releasably secure the pump against upward travel upon upstroke of the pump rod.

An additional object of the invention is to provide a top lock, for an insert type oil well pump, which remains locked during normal reciprocation of the pump rod, but is automatically released—for withdrawal of the pump to the surface—upon an upstroke of the pump rod beyond its normal point of maximum rise.

A further object of this invention is to provide a releasable lock, as in the preceding paragraph, which includes a normally laterally outwardly sprung, longitudinally extending leaf spring finger unit on a stationary part of the pump and which unit bears at its upper end against the top lock ring from below; there being a spring release sleeve on a reciprocating part of the pump in position to slide over and compress the spring unit, to release position, upon upward motion of the pump rod beyond said normal point of maximum rise.

A further object of the invention is to provide a practical and reliable top lock for insert type oil well pumps, and yet one which will be exceedingly effective for the purpose for which it is designed.

These objects are accomplished by means of such structure and relative arrangement of parts as will fully appear by a perusal of the following specification and claims.

In the drawings:

Fig. 1 is a fragmentary sectional elevation of an insert type pump, illustrating the novel top lock in engaged or operative position.

Fig. 2 is a similar view, but shows the top lock in released position preparatory to withdrawal of the pump from the well.

Referring now more particularly to the characters of reference on the drawings, the invention is embodied in connection with an insert type oil well pump including the following:

The numeral 1 indicates the suspension tubing of a pumping assembly; such tubing being threadingly connected, at its lower end, with a coupling assembly 2, while the upper end of the pump jacket 3 is threadingly connected to the lower end of said coupling assembly. The stand-

ing valve unit (not shown) is fitted on the lower end of the pump jacket 3.

The reciprocating pump rod, which is indicated at 4, extends downwardly through the suspension tubing 1 and coupling assembly 2, into pump jacket 3; being affixed, at its lower end, to the traveling valve (not shown). However, the traveling valve is fixed to an upstanding tubular reciprocating plunger or insert jacket 5, including lines 6, as shown, for example, in U. S. Patent No. 2,026,465.

The tubular reciprocating plunger 5 is thus actuated by the pump rod 4, and rides in close fitting guided relation about a stationary tubular plunger 7.

The stationary plunger 7 is threadingly connected, at its upper end, to the lower end of a tubular suspension mandrel 8; which runs upwardly into the coupling assembly 2, but terminates short of the upper end of the latter.

Said coupling assembly 2 includes an upper coupling 9 and a lower coupling 10 threaded together and clamping therebetween what is known as a top lock ring 11; the internal diameter of the top lock ring 11 being somewhat lesser than the internal diameter of the coupling assembly 2.

Above the top lock ring 11 is a cylindrical sealing head 12 tapered at the lower end, with said tapered lower end matchingly engaging with an upwardly and outwardly flaring, annular seat 13 formed internally in the upper portion of the top lock ring 11. The upper end of the tubular suspension mandrel 8 is threadingly connected into the sealing head 12 whereby the insert pump assembly is effectively suspended within the pump jacket 3.

In order to prevent the insert pump, including the plunger 5 and stationary plunger 7, from moving upwardly in the tubing upon the normal upstroke of the reciprocating pump rod 4, there is provided the following top lock:

Adjacent its lower end, but above the stationary plunger 7, the suspension mandrel 8 has a collar 14 threaded thereon, which collar is locked in place from below by a lock nut 15. The collar 14 includes, in integral relation, a plurality of circumferentially spaced, longitudinally upwardly extending leaf, or flat, spring fingers 16. These fingers 16 normally spring apart sufficient to they abut, at their ends, against the lower end of the top lock ring 11, which lower end is beveled, as at 17. At this point it should be noted that the outside diameter of the collar 14 from which the spring fingers 16 have their inception is of considerably lesser outer diameter

than the inner diameter of the top lock ring 11. This is to permit the collar and finger when compressed to be confined within a retaining and release sleeve 18, which also is capable of passing through ring 11. This sleeve is fixed, at its lower end, to the tubular reciprocating plunger 5 at the upper end of the latter; such sleeve surrounding the stationary plunger in spaced relation, and running in guided relatively close fitting relation with the lower end portion of the tubular suspension mandrel 8.

This allows the reciprocating plunger and connected parts to be initially lowered into the suspension tubing without possibility of the spring fingers expanding and possibly catching or jamming ahead of time. However, as soon as the sleeve 18 passes through the ring 11 and the head 12 engages seat 13, further lowering of the fingers is prevented, while sleeve 18 continues to drop as the plunger 5 to which said sleeve is connected moves to operating position.

As the sleeve pulls away from the fingers, the latter are free to expand, and being then immediately below the ring 11, engage the taper 17 of the same to provide the desired positive lock and preventing upward displacement of the insert type pump in the pump jacket 3 during the normal upstroke of the pump rod 4 and connected parts of said pump.

Upon normal reciprocation of the pump rod 4 and the tubular reciprocating plunger 5, the spring release sleeve 18 works entirely below the spring fingers 16 and the lock formed by the latter is not disturbed. The normal upper limit of travel of the spring release sleeve 18 is shown in Fig. 1.

When it is desired to release the pump for withdrawal, the pump rod 4 is actuated through an up-stroke considerably beyond its normal point of maximum rise. When this occurs the sleeve 18 passes upwardly about the fingers 16, springing them inwardly and confining them for passage upwardly through the top lock ring 11. As is necessary, the outside diameter of the plunger 5, as well as that of the remaining parts of the pump and the sleeve 18, must be such that they too can pass upwardly through the ring 11.

In the above described manner, the locked-in-place insert type pump can be readily and quickly released for withdrawal from the well upon nothing more than an up-stroke of the pump rod 4 beyond its normal point of maximum rise, and a positive locking, as well as a positive interlocking, action is provided.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as set forth herein.

Having thus described the invention, the following is claimed as new and useful, and upon which Letters Patent are desired:

We claim:

1. In an oil well pump which includes a pump jacket suspended by a coupling assembly from tubing, and a reciprocatory pump rod extending into the pump jacket from within the tubing; a pair of cooperative tubular plungers in the pump jacket, one of the plungers reciprocating with

the pump rod, and mechanism limiting downward motion of the other plunger beyond a predetermined point and releasably locking said other plunger against travel with the pump rod on the upstroke; said mechanism including a tubular mandrel secured to the other plunger and extending upward into the coupling assembly, an internally exposed top lock ring in said coupling assembly, the mandrel projecting through the ring, a member on the mandrel above and seating on said ring, a locking element releasably engaging the ring from below, said locking element being fixed with respect to the mandrel, and a member movable with the pump rod operative to engage and release said locking element upon other than normal axial motion of said pump rod.

2. In an oil well pump which includes a pump jacket suspended by a coupling assembly from tubing, and a reciprocatory pump rod extending into the pump jacket from within the tubing; a pair of cooperative tubular plungers in the pump jacket, one of the plungers reciprocating with the pump rod, and mechanism limiting downward motion of the other plunger beyond a predetermined point and releasably locking said other plunger against travel with the pump rod on the upstroke; said mechanism including a tubular mandrel secured to the other plunger and extending upward into the coupling assembly, an internally exposed top lock ring in said coupling assembly, the mandrel projecting through the ring, a member on the mandrel above and seating on said ring, a locking element releasably engaging the ring from below, said locking element being fixed with respect to the mandrel, and a member movable with the pump rod operative to engage and release said locking element upon other than normal axial motion of said pump rod.

3. In an oil well pump which includes a pump jacket suspended by a coupling assembly from tubing, and a reciprocatory pump rod extending into the pump jacket from within the tubing; a pair of cooperative tubular plungers in the pump jacket, one of the plungers reciprocating with the pump rod, and mechanism limiting downward motion of the other plunger beyond a predetermined point and releasably locking said other plunger against travel with the pump rod on the upstroke; said mechanism including a tubular mandrel secured to the other plunger and extending upward into the coupling assembly, an internally exposed top lock ring in said coupling assembly, the mandrel projecting through the ring, a member on the mandrel above and seating on said ring, a locking element releasably engaging the ring from below, said locking element being fixed with respect to the mandrel, and a member movable with the pump rod operative to engage and release said locking element upon upward motion of the pump rod beyond its normal point of rise; said member being fixed in connection with and upstanding from said one plunger for travel therewith.

4. An oil well pump, as in claim 3, in which the locking element is a longitudinal leaf spring which is normally sprung outward for ring engagement.

5. An oil well pump, as in claim 3, in which the locking element is a longitudinal leaf spring which is normally sprung outward for ring engagement, and said release member is a sleeve adapted to ride up said spring and urge it inward to a position clear of and for passage through said ring.

6. In an oil well pump which includes a pump jacket suspended by a coupling assembly from tubing, and a reciprocatory pump rod extending into the pump jacket from within the tubing; a pair of cooperative tubular plungers in the pump jacket, one of the plungers reciprocating with the pump rod, a radially inwardly extending top lock ring in said coupling assembly, a tubular mandrel upstanding from the other plunger about the pump rod and projecting through the ring from below, a head on the mandrel seating on the ring from above, a locking element releasably engaging the ring from below, said locking element being fixed with respect to the mandrel, and a member movable with the pump rod operative to engage and release said locking element upon other than normal axial motion of said pump rod.

7. In an oil well pump which includes a pump jacket suspended by a coupling assembly from tubing, and a reciprocatory pump rod extending into the pump jacket from within the tubing; a pair of cooperative tubular plungers in the pump jacket, one of the plungers reciprocating with the pump rod, a radially inwardly extending top lock ring in said coupling assembly, a tubular mandrel upstanding from the other plunger about the pump rod and projecting through the ring from below, a head on the mandrel seating on the ring from above, a collar secured to the mandrel in spaced relation below the ring, a longitudinal spring upstanding from the collar normally sprung outward and end engaging the ring from below, and a member movable with the pump rod below the ring operative to ride up said spring and urge it upward, to a position clear of and for passage through the ring, upon upward motion of the pump rod beyond its normal point of rise.

8. In an oil well pump which includes a pump jacket suspended by a coupling assembly from tubing, and a reciprocatory pump rod extending into the pump jacket from within the tubing; a pair of cooperative tubular plungers in the pump jacket, one of the plungers reciprocating with the pump rod, a radially inwardly extending top lock ring in said coupling assembly, a tubular mandrel upstanding from the other plunger about the pump rod and projecting through the ring from below, a head on the mandrel seating on the ring from above, a collar secured to the mandrel in spaced relation below the ring, a longitudinal spring upstanding from the collar normally sprung outward and end engaging the ring from below, and a sleeve movable with the pump rod below the ring operative to ride up said spring and urge it upward, to a position clear of and for passage through the ring, upon upward motion of the pump rod beyond its normal point of rise.

9. In an oil well pump which includes a pump jacket suspended by a coupling assembly from tubing, and a reciprocatory pump rod extending into the pump jacket from within the tubing; a pair of cooperative tubular plungers in the pump jacket, one of the plungers reciprocating with the pump rod, a radially inwardly extending top lock ring in said coupling assembly, a tubular mandrel upstanding from the other plunger about the pump rod and projecting through the ring from below, a head on the mandrel seating on the ring from above, a collar secured to the mandrel in spaced relation below the ring, a circumferential row of leaf springs upstanding from the collar normally sprung outward and end engaging the ring from below, and a sleeve upstanding from and movable with said one plunger operative to ride up said row of springs and urge them inward, to a position clear of and for passage through the ring, upon upward travel of the pump rod and said one plunger above the normal point of rise.

10. In an oil well pump which includes a pump jacket suspended by a coupling assembly from tubing, and a reciprocatory pump rod extending into the pump jacket from within the tubing; a pair of cooperative tubular plungers in the pump jacket, one of the plungers reciprocating with the pump rod, a radially inwardly extending top lock ring in said coupling assembly, a tubular mandrel upstanding from the other plunger about the pump rod and projecting through the ring from below, a head on the mandrel seating on the ring from above, a collar secured to the mandrel in spaced relation below the ring, a circumferential row of leaf springs upstanding from the collar normally sprung outward and end engaging the ring from below, and a sleeve upstanding from and movable with said one plunger operative to ride up said row of springs and urge them inward, to a position clear of and for passage through the ring, upon upward travel of the pump rod and said one plunger above the normal point of rise; the maximum outside diameter of the plungers and sleeve being less than the inside diameter of the ring.
